United States Patent Office.

LOUIS GODDU, OF BOSTON, MASSACHUSETTS, ASSIGNOR TO ELMER TOWNSEND, OF SAME PLACE.

Letters Patent No. 97,192, dated November 23, 1869.

IMPROVEMENT IN MACHINES FOR NAILING SHOE-SOLES WITH WIRE.

The Schedule referred to in these Letters Patent and making part of the same.

To all persons to whom these presents may come:

Be it known that I, LOUIS GODDU, a citizen of the Dominion of Canada, having resided in the United States the year preceding, and made oath of intention to become a citizen thereof, and being now a resident of Boston, of the county of Suffolk, and State of Massachusetts, or the vicinity thereof, have made a new and useful invention of Improvements in Machinery having reference to the Nailing of Shoe-Soles, or various other articles; and I do hereby declare the said invention, or improvements in nailing-machinery, to be fully described in the following specification, and represented in the accompanying drawings, of which—

Figure 1 is a front elevation, and

Figures 2 and 3, opposite side elevations of a shoe-sole-nailing machine embodying my said invention.

In many of its essential characteristics, the machine is analogous to that described and represented in the specification and drawings of Letters Patent No. 77,104, dated April 21, 1868, and granted to Joseph T. Sargent.

It, however, contains new and useful mechanism for operating the movable cutter and the wire-transferrer.

It also contains a slide-gauge, to be actuated by the hand or finger of a person while grasping the handle of the frame or stock of the machine, and the machine may be in operation, such slide-gauge being for causing the feeding-mechanism to feed the wire forward, or deliver it, in such lengths or distances as, from time to time, may be desirable, as the sole to be nailed may either increase or diminish in thickness.

In the drawings—

A denotes the stock or frame, for supporting the main operative parts of the machine, such stock being provided at its upper part with a handle, B, which is to be grasped by the left hand of a person, in order to hold the machine in an upright position, while it may be at work, and he may be operating it by turning a crank, C, fixed to one end of a driving-shaft, D. The said shaft, having its journals supported in bearings *a a*, carries a spur-gear, E, which engages with a pinion, F, fixed on another shaft, G, on whose outer end a fly-wheel, H, is fastened.

The gear E has one continuous cam-groove, b, made in one side of it, as shown in Figure 4, which is a side elevation of the said gear, and within its opposite side are two other continuous cam-grooves, as shown at *c* and *d* in Figure 5, which is an opposite side view of the said gear E. These two cam-grooves receive friction-wheels, arranged on pivots projected from a feeding-lever, I, which is pivoted to the stock, as shown at *e*.

Within the lever is a rectangular slot, *f*, which receives a slide, *g*, through which the pivot-pin *e* extends, the whole being to enable the lever to play up

and down, or lengthwise of it, as well as to oscillate on its fulcrum.

There is also applied to the stock or frame, a feed-wheel, *h*, provided with a ratchet, *i*, and a presser-wheel, *k*, held in place by a spring, *m*.

The wire *l*, to be cut and driven, goes between the two wheels *h k*, thence through the spring *m* and a guide, *n*, projected from the frame or stock.

A lever, *o*, pivoted to the stock at *p*, has jointed to its lower end a draw-pawl, *q*, which engages with the ratchet *i*.

A spring, *k'*, fixed to the frame and the lever *o*, serves to retract the draw-pawl in the ratchet, the extent of rearward movement of such pawl being determined by means of a slide-gauge, *r*, and a stop-pin, *s*. The said stop-pin extends from the lever *o* in manner as represented.

The gauge *r*, formed as shown in the drawings, and particularly as exhibited in Figure 6, (which is a vertical section, taken through it and the part for sustaining it, Figure 7 being a top view of such part and the stops of the gauge,) is arranged in a hole or passage, *t*, and has its front end tapering or wedge-shaped. At its rear, the gauge is bent somewhat in the shape of the trigger of the lock of a gun. The part *t'*, so bent up, extends between two stops *u u*, which limit the longitudinal movements of the gauge.

The part *t* is arranged so as to enable a person, while grasping the handle in one hand, to apply his fifth finger to such part *t*, and move the gauge lengthwise, as occasion may require.

A spring, *v*, applied to the gauge and the stock, serves to retract such gauge, or move it in a direction opposite to that by which it may be moved by the finger, as explained.

The wedge-end of the gauge determines, with the stop-pin *s*, the extent of back movement of the draw-pawl on the ratchet, as the further the gauge may be moved by the finger, the less will be such movement of the pawl, and, as a consequence, the shorter will be the advance of the nail-wire.

From the above, it will be seen that the operative, by means of the gauge, arranged and applied in manner as described, can readily control or regulate the extent of such advance of the wire.

Such wire, after each advance, will be extended across a stationary cutter or knife, *w*, arranged within and so as to project from the guide *n'*.

A movable cutter, *x*, fixed in the lesser arm *y* of a lever, *K*, operates with the stationary cutter to sever the wire.

Figure 8 is a front view, and

Figure 9, a top view of the lever *K*.

Figure 10 is a top view, and

Figure 11, a side view of the lever *L*.

These two levers K L have concentric fulcra, which extend transversely through the stock; that is to say, from the lever K, a tube, z , projects into and is pivoted in the stock. This tube receives a short shaft or fulcrum, a , on one end of which is the transfer b . The tube has fixed to it the tail c of the lever K. The transfer, the part a , and the arm or tail c constitute the lever K.

The tail c or i of each lever has a cam-slot, d or e , made through it, to receive one end of the lower cross-bar f of an inverted "T-piece," M.

From the upper end of the said "T-piece," a stud extends into the cam-groove b of the gear E. This extends into the cam-groove b of the gear E. This cam-groove, during the revolution of the gear, will operate the "T-piece," which, acting in the cam-grooves of the tails of the levers K L, will put such levers in movement at the proper times, whereby not only will the wire be severed by the cutters, but the transfer will be revolved, so as to bring a wire-receiving passage, c , made through it, into line with the wire, in order that the said wire, previously to being severed, may be received into the passage.

After the wire may have been cut off, the transfer will be turned, so as to bring the said wire-passage into a vertical position, in order to enable a wire-driver, shown at N, during its descent, to enter the passage and force the piece of wire out of it, and drive it into a sole, in case the machine may be resting on one.

This driver, and an awl, O, are fixed to the lower part of a carrier, P, such carrier being arranged as represented, and so applied to the frame as to be capable of sliding rectilinearly therein.

A cam or wiper, R, fixed on the driving-shaft, by acting against an adjustable slider, S, clamped on the carrier P, serves to elevate the carrier, and to contract a helical spring, g , (arranged on the said carrier,) which, on the instant the cam may have passed the slider S, will react and force the carrier downward, thereby causing the nail to be driven into the sole, and an awl-hole to be made simultaneously therein.

An adjustable edge-gauge, h , held in place by a clamp-screw, i , is applied to the lower part of the stock or frame A.

In operating with the above-described machine, the lower part of the transfer is to be first placed on a sole, the edge-gauge h being against the continuous edge of the sole.

The attendant is to grasp, with his left hand, the handle of the stock A, and turn the crank C with the other hand. In so doing, he will cause, through the mechanism, the machine to have intermittent movements along the sole, each advance of it being a like distance.

During each interval of rest of the machine on the sole, the nail-driver and the awl will be raised, the transfer will be revolved back to receive the wire, the said wire will be advanced into the transfer, and be severed or cut by the cutters, after which the transfer will be turned back to its first position, and the driver and awl will be forced downward, thereby causing the nail to be expelled from the transfer and driven into the awl-hole of the sole, and the awl to form in the sole a hole for the reception of the next nail to be driven.

In the above-described machine,

I claim, as my invention, the following, viz:

The combination, as well as the arrangement, substantially as described, of the stationary cutter w , the movable cutter x , the transfer b , their concentric fulcra or shafts z a , the slotted tails c i thereof, the movable "T-piece" M, and its operative cam-wheel E, the whole being applied to the stock or frame, and connected with mechanism for advancing the wire, severing it, and driving it, all substantially as specified.

Also, the arrangement of the slide-gauge r , as set forth, with the handle B of the stock A, and with the stop-pin s of the pawl-lever of the wire-feeding mechanism.

Also, the combination and arrangement of the slider-gauge r , as set forth, its stops u u , and operative spring v , with the stock A and its handle B, and the stop s and operative lever o of the wire-feeding mechanism.

LOUIS GODDU.
